CLAIM

The ornamental design for a glider frame with canopy, as shown and described.

DESCRIPTION

FIG. 1 is a perspective view of the first embodiment of a glider frame with canopy showing my new design;

FIG. 2 is a top plan view of the first embodiment thereof; FIG. 3 is a right side elevation view of the first embodiment thereof; the left side being the same;

FIG. 4 is a front elevation view of the first embodiment thereof;

FIG. 5 is a rear elevation view of the first embodiment thereof;

FIG. 6 is a bottom plan view of the first embodiment thereof;

FIG. 7 is a perspective view of the second embodiment of a glider frame with canopy showing my new design;

FIG. 8 is a top plan view of the second embodiment thereof;

FIG. 9 is a right side elevation view of the second embodiment thereof; the left side being the same;

FIG. 10 is a front elevation view of the second embodiment thereof;

FIG. 11 is a rear elevation view of the second embodiment thereof; and,

FIG. 12 is a bottom plan view of the second embodiment thereof.

The broken line showing of a glider and a canopy is for illustrative purposes only and forms no part of the claimed design
